EXTENSIBLE CHAIR

Adam J. May, Rochester, N. Y., assignor to Ritter
Dental Manufacturing Co., Inc., Rochester,
N. Y., a corporation of Delaware

Application September 16, 1929, Serial No. 392,880

18 Claims. (Cl. 155—25)

The present invention relates to extensible chairs and has for one object to provide an improved chair of this class having one or more columns or sections to be raised and lowered, the 5 invention being particularly adaptable for use on dental, surgical and barber chairs.

A further object of the invention is to provide improved means for controlling the operation of electrically driven lifts for chair seats or supports, and more particularly, means by which to control the operations of a reversible electric motor for operating the lift whereby the up and down movements of one or more parts are utilized together with manual control means 15 for starting, stopping, and reversing the motor when desired.

A further object of the invention is to provide an extensible motor actuated chair lifting mechanism having improved electrical control 20 devices for rendering the motor ineffective when the parts have reached different positions of adjustment, said devices being coordinated to effect control of the movements of the extensible parts in a manner to simplify the work of the 25 operator.

A further object of the invention is to provide in combination with a motor operated lift, such for example, as an electrically driven chair column or section, an improved switch 30 for controlling the motor circuit, arranged for operation manually as well as automatically by the up and down movements of the column whereby to avoid the expense of applying separate limit and reversing switches for controlling 35 the operation of the motor as heretofore employed in extensible chairs or lifts of the present type.

A further object of the invention is to provide in combination with a movable chair section and a reversible electric motor for operating the same, a unitary switch for reversing the motor circuit having spaced operating elements so arranged as to permit of manual control of the switch from one or more points and also 45 having operating means associated with a movable part of the chair for automatic operation whereby to break the circuit when said part reaches different predetermined positions.

A further object of the invention is to provide 50 an improved switch for reversible electric motors designed both for manual and automatic operation, the switch being of simple construction, comparatively inexpensive to manufacture and efficient in service.

55 A further object of the invention is to pro-

vide an improved electric switch of the mercury tube type designed particularly for use as a combined reversing and limit switch for operation by different control devices but independently operable by a single control device. 60

To these and other ends the invention resides in certain improvements and combinations of parts, all as will be hereinafter more fully described, the novel features being pointed out in the claims at the end of the specification. 65

In the drawings:

Fig. 1 is a side elevation of a chair embodying the invention;

Fig. 2 is a part sectional plan of the base of the chair showing the motor and seat raising 70 columns;

Fig. 3 is a fragmentary sectional elevation partially illustrating the operating means for the seat raising columns;

Fig. 4 is a sectional elevation of the switch 75 taken substantially on line 4a—4a of Fig. 8;

Fig. 5 is a sectional elevation taken substantially on line 5a—5a of Fig. 8 with the switch in one of its circuit closing positions;

Fig. 6 is a similar section of the switch in 80 circuit breaking position;

Fig. 7 is a view similar to Fig. 4 with the switch in one of its circuit closing positions;

Fig. 8 is a fragmentary sectional plan through the base of the chair showing the switch and 85 operating pedals therefor with parts of the switch in section;

Fig. 9 is a sectional plan of one of the mercury tube holders;

Fig. 10 is a sectional elevation taken substantially on line 10a—10a of Fig. 8;

Fig. 11 is a fragmentary sectional elevation taken on line 11a—11a of Fig. 8 showing the operating means for the switch designed to be 95 actuated by one of the chair columns;

Fig. 12 is a sectional elevation taken on line 12a—12a of Fig. 8;

Fig. 13 is a view similar to Fig. 11 with the switch in a position corresponding to that shown 100 in Fig. 7 to which it is moved by depressing one of the pedals;

Fig. 14 is a view in elevation showing one of the mercury tube operating segments;

Fig. 15 is a part sectional elevation showing 105 the segment coupled with one of the operating elements therefor arranged to be actuated by the vertical movement of the chair column, and

Fig. 16 is a diagrammatic view illustrating the motor circuit arrangement. 110

Similar reference numerals throughout the several views indicate the same parts.

In the present invention I have provided a chair having extensible sections with a reversible electric motor for operating any suitable lifting mechanism for one or more sections. Heretofore it has been customary to provide both a reversing switch and a limit switch on different parts of the chair to effect reversal of the motor and breaking of the circuit when the sections approach the limits of their movements, in cases where the operator fails to release the pedal. In the present invention I provide a combined limit and reversing switch to be manually actuated under normal operating conditions and arranged for automatic operation preferably by a moving part of the lifting mechanism or one of the sections, in the case of an emergency.

The switch embodies a new and novel construction in which two cooperating mercury tube switch elements are employed for controlling the motor circuits, together with improved operating means for said elements which can be conveniently controlled from different sides of the chair base.

By combining the limit or safety switch with the operating or reversing switch the number of parts used are considerably reduced and the cost of production lowered while the efficiency of the circuit control mechanism is increased over prior arrangements embodying separate switches.

Referring to the drawings, 10 represents the base of the chair within which is disposed inner and outer columns or sections 11 and 12 respectively and with which is associated a reversible electric motor 13 for operating the sections to raise the chair seat frame 14. The operating means interposed between the motor and extensible sections may be of any preferred type suitable for the purpose. The motor driven operating means shown in the drawings by way of example is the same as that disclosed in Patent No. 1,700,741, issued February 5, 1929. This mechanism which will be briefly described comprises a worm shaft 15 suitably connected with the motor shaft 15a. A worm 16 on the worm shaft meshes with a worm wheel 17 on a shaft 18 carrying a pinion 18a for driving a gear 19 which serves to drive a similar gear 19a on a shaft 20. The shaft 20 has its outer end journaled in the gear casing 21 and its inner end journaled in a standard 22 projecting from the bottom 23 of the base into the column 11. The drive shaft 20 has a sprocket 24 thereon for driving a chain 25 extending over a pulley 26 journaled in the top of the standard, the chain extending under a pulley (not shown) journaled on the bottom of the outer column 12, from which pulley the chain extends upwardly outside of the column 12 to a point where it is anchored upon the upper end of the base 10. The opposite end of the chain is carried under the sprocket and is extended upwardly a short distance and connected with a vertically disposed rod (not shown) having its upper end yieldably connected with the top of the inner column 11 all as clearly shown in the above mentioned patent. The sprocket chain serves to raise the outer column 12 and the inner column is raised by the outer column by means of a pair of chains or flexible elements 27 extending over pulleys 28 journaled on the upper end of the outer column. The chains have their lower ends connected with lugs 29 and 30 carried respectively by the inner

column 11 and the bottom 23 of the base as indicated in Fig. 3.

The base 10 is provided with an opening at one side which is closed by a bracket or plate-like member 31 forming a support for the switch, the support being removably secured to the base preferably by a suitable number of screws or bolts (not shown). At a point opposite the support the base is provided with a vertically disposed wall portion 32 for receiving certain parts of the switch mechanism described hereinafter.

The movable elements of the switch preferably comprise two mercury holding tubes 33 and 33a constructed of glass or other suitable material and having the required amount of mercury, indicated at 34, therein. The tubes are similarly constructed, but are reversed so that in either of the tilted positions shown in Figs. 5 and 7, three of the contacts of one tube and two of the other will project within the mercury, regardless of which circuit closing position the tubes may occupy. The contacts of the left hand tube shown in Fig. 4, are indicated by the characters 35 to 38 inclusive and the corresponding contacts of tube 33a are indicated by the characters 35a to 38a inclusive. These contacts are electrically connected with the reversible motor as illustrated in the wiring diagram shown in Fig. 16 and fully explained hereinafter.

The tubes are swung from the normal inoperative position shown in Fig. 6 to either circuit closing position by a pair of segments or pivoted elements 39 and 40 which have intermeshing teeth as shown, the segment 40 being arranged to operate segment 39 when swung in either direction from the normal position shown in Fig. 6.

The tubes are each carried by an oscillatory support or rocker best shown in Figs. 9 and 10, each comprising a plate-like arm 41 having 115 struck upwardly therefrom a central yoke-like portion 41a on the inner end of which is fixed a bearing 42 and on the outer end a spindle 43. The bearing 42 is held in a sleeve-like portion of a bell-crank lever 44 journaled in the wall 32 120 of the pedestal base and the spindle 43 is journaled in a sleeve 45 carried by the front wall of the switch support 31, Fig. 10. A screw 46 threaded into the end of the spindle 43 engages a washer 47 seated on the wall 31 to limit the 125 inward movement of the oscillatory tube support. The arm 41 carries on its inner face a holder for the mercury tube comprising a plate 48 having a plurality of spring-like fingers 49 partially surrounding the tube and permitting it to be removed from the holder when desired.

The segments 39 and 40 are seated on the outer faces of the arms 41 and are held against outward movement by the sleeve bearings 45 in which the spindles 43 are journaled. The segments are each coupled with one of the arms for movement relative thereto and are arranged under normal conditions of operation of the chair columns to move with the arms upon oscillation of the same. The segments serve to operate the arms since the latter have pins 50 projecting through slots 51 in the segments in which the pins are centrally held each by the opposite ends of a spring 52 coiled about the sleeve bearing 45, Fig. 10. The ends of the spring are crossed, Fig. 15, and extend on opposite sides of a pin 53 on the segment and into engagement with the pin 50 on the arm, so that under normal operation the spring constitutes 130

- the means for actuating the arms, on which the mercury holding tubes are secured. The position of the segment 40 relative to the arm 41 as shown in Fig. 15 is that which results when 5 the operator continues to hold down the pedal as the chair column 12 reaches one of its extreme positions of movement. In this case a device operated by said column and explained hereinafter will rock the bell-crank levers 44, 10 the bearings 42 and arms 41 against the resistance of the springs 52 so that the arms and tubes thereon are brought to the horizontal circuit breaking position shown in Figs. 6 and 15. As soon thereafter as the pedal is released the 15 segments 39 and 40 will be automatically returned to normal position, partially by the portion of the spring 52 acting on the pin 53 of the segment but more positively by means herein-after described. 20 Means is provided for preventing a quick throw of the mercury tubes from circuit closing to circuit opening position in order to prevent splashing or undue shifting of the mercury within the tubes whereby to avoid accidental 25 closing of the circuit should the operator suddenly release the pedal. In carrying out this idea the preferred means employed is in the form of a dashpot although other suitable means may be substituted therefor if desired. The 30 dashpot, which may be either of pneumatic or hydraulic type, comprises a closed cylinder 54 having a piston 54a therein actuated by a stem 55 pivotally connected with an arm 56 on the segment 40. The opposite segment 39 carries 35 an arm 57 which is pivotally connected with the cylinder 54. In the normal position of the dashpot as shown in Fig. 6, the piston will occupy a position substantially midway between the ends of the cylinder. However when the 40 switch is operated to the extreme positions shown in Figs. 5 and 7 and the pedal released, the piston will be moved in a direction to afford the desired cushioning effect and the mercury tubes will be slowly returned to the normal position 45 shown in Fig. 4 without unduly agitating the mercury.
- Operation of the segments 39 and 40 may be effected by any suitable means for swinging them about their axes to cause shifting of the 50 mercury tubes for the purpose of opening and closing one or more circuits by a change in the position of the mercury within the tubes or by other means responsive to the action of gravity which may be suitable for the purpose, either in 55 the form of a liquid or a solid.
- The present operating means shown by way of example, comprises a plurality of foot pedals on the base of the chair, each of which is operable to shift the mercury tubes from normal to a 60 circuit closing position. With the present arrangement of pedals, best shown in Figs. 2 and 8, the operator when standing at the back of the chair can operate the switch to effect up and down movement of the chair columns by depressing one or the other of a pair of pedals 58 and 59 extending from a central hub portion 60 which is keyed on a member 61 journaled in a bearing 62 on the bracket 31, Fig. 12. In order to obtain a relatively long bearing for the pivot member 61, a lug 63 is cast on the bracket 31 and is bored out to receive the inner end of the pivot member which has an operating gear 64 fixed thereon and held against longitudinal displacement by a screw 65. The teeth of the gear 64 are in mesh with those of two 65 gear segments 66 and 67 which are fixed on pivot members 68 journaled in bearings 69 of the bracket 31, the segments being held in position by screws 70, Figs. 5 and 10. On the other ends of the pivot members 68, pedals 71 and 72 are fixed which extend in opposite directions and somewhat beyond the pedals 58 and 59 for convenient control by the operator when he is standing at the sides of the chair, in which case pedals 58 and 71 will be depressed in raising and lowering the chair column if the operator is standing at one side of the chair and if he is at the opposite side, pedals 59 and 72 will be depressed for the same purpose. On the other hand if the operator is standing at the back of the chair pedals 58 and 59 will be depressed to effect the closing of the switch for the up and down movements of the chair sections. 70
- Operation of both mercury tubes in opposite directions is effected through the rocking of segment 67, the teeth of which are in mesh with those on the lower portion of segment 40. The oscillation of segment 67 may be effected by depressing pedal 71 which is directly connected 75 with said segment or by depressing pedal 72 which is directly connected with segment 66, the latter being operatively connected with the gear or segment 64 which is in operative engagement with segment 67. 80
- Return of the pedals and the mercury tubes to normal circuit breaking position from either circuit closing position is effected preferably by a spring 73 coiled about the bearing portion 63 of the pivot member 61 for operating the gear 64, Fig. 12. The ends of the spring are crossed and normally engage opposite sides of an inwardly extending member 74 on the wall of the bracket 31. A similar member 75 underlies the member 74 and is fixed on an extended portion 76 of the gear 64. Upon rocking the gear to the right or left of the position shown in Fig. 4, the projecting member 75 thereon will either move one or the other end portions of the spring in a direction to increase the tension of the spring and upon release of any one of the pedals the spring will return the gear 64 to central position, thus causing the return of the segments 39 and 40 and the tubes thereon to the normal circuit breaking position shown 85 in Fig. 4, during which return movement the dashpot 54 will check the speed of the parts and prevent undue agitation of the mercury within the tubes. 90
- The bracket 31 and all parts thereon may be 95 inserted upon and withdrawn from the chair base in a unit since the members 42 are arranged to slide within the sleeve-like portions of the bell-crank levers 44 by reason of the fact that said members are slotted at 42a to receive the pins 43a carried by said levers. 100
- Means by which the switch is automatically moved to circuit breaking position when the chair column or section 12 approaches its limits of movement includes the bell-crank levers 44 and a yoke 77 connected with the arms of the levers by means of pins 78 disposed in slots 79 formed in said arms, the slots permitting the arms to swing through the required arcs upon operating the pedals to move the tubes to the different circuit closing positions. The yoke carries an upstanding rod 80 on the upper end of which is disposed a head 81, while spring 82 is secured upon the rod adjacent the head for a purpose which will presently appear. The 105

column 12 has a lug 83 thereon which is provided with an opening through which the rod projects. In cases where the operator may not think to release the pedal before the column reaches the limits of its up and down movements, the lug, on the upward stroke of the column will engage the spring 82 and cause the rod to lift the yoke whereby to swing the tube holding arms 41 to normal circuit breaking position. The same result is afforded on the downward movement of the column by reason of the fact that the lug will engage and shift the yoke to swing the tube holding arms from the position shown in Fig. 5 to that shown in Fig. 11, assuming of course that the operator has failed to release the pedal.

The mercury tubes are so designed that either can be used as a switch, independently of the other, for controlling one or more electric circuits. By mounting one of the tubes on a pivoted member, such as the segment 40, the latter can be operated by the gear segment 67 and pedal 71 to adjust it either to a horizontal circuit breaking position or to two different circuit closing positions, in one of which the contacts 37a and 38a will engage the mercury as shown in Fig. 5 and in the other of which the contacts 35a and 37a will project into the mercury with the tube in the position shown in Fig. 7, the contact 36a being retained or omitted as may be required. Thus each tube constitutes a switch by itself in which the contact 37a in tube 33a would be common to both circuits.

The D. C. motor shown in Fig. 16 is indicated generally by the reference character 13a and embodies the usual armature 84 and series and shunt coils 85 and 86 respectively. In the circuit closing position of the mercury tubes shown the contacts engaged by the mercury are indicated by the reference characters 35, 36, 37, 37a and 38a, and it is these contacts which are included in the circuit. The line wire 87 is connected with the series coil 85 which is connected with contact 38a by wires 88 and 89. Contact 37a projecting within the mercury is connected with the armature by a wire 90 and leading from the armature is a wire 91 which is connected with contact 37 in tube 33 which corresponds to contact 37a in the tube 33a. Contact 35 projects into the mercury of tube 33 and is thus connected with contact 37, contact 35 being connected with wire 92 which leads to line wire 93. The shunt coil 86 has one end connected to wire 88 and the other end is connected with wires 94 and 95, the latter of which extends to contact 36 projecting into the mercury of tube 33 whereby to complete the shunt circuit.

Reversal of the motor circuit will be effected by shifting the tubes to the position shown in Fig. 7, in which case contacts 37 and 38 will engage the mercury within tube 33 and contacts 35a, 36a and 37a will project into the mercury within the tube 33a to complete the circuit through certain wires common to both circuits and additional wires 88a, 93a and 94a connected respectively with wires 88, 93 and 94, it being understood that on reversing of the circuit contacts 35, 36 and 38a will no longer project within the mercury. It should be remembered, however, that in either closing position of the switch, contacts 37 and 37a are partially immersed within the mercury and are therefore common to both circuits. In the normal posi-

tion of the switch none of the contacts will engage the mercury other than 37 and 37a and the circuit can be closed only by shifting the mercury tubes from normal position simultaneously to one of the two circuit closing positions shown.

In order to prevent the possibility of burning out the contacts through arcing when making and breaking the circuit, a suitable condenser 95 is interposed in the circuit which will operate, through concentration of the current, to protect the contacts when the mercury flows to or from engagement therewith on shifting the tubes to and from normal position.

While a D. C. motor is shown for operating the chair raising mechanism an A. C. motor may be substituted therefor if desired, in which case the wires leading to contacts 36 and 36a will be omitted since the shunt coil will not be used.

In the raising and lowering operations of the chair columns or sections the operator, if standing at the back of the chair, will depress one of the pedals 58 or 59 depending on whether or not the chair is to be moved up or down. Assuming that it is required to depress pedal 59 in order to cause the column to move upwardly then the mercury holding tubes will be moved to the circuit closing position shown in Fig. 7, and the motor will begin to operate to lift the column. As long as the operator holds the pedal 59 depressed the circuit will remain closed unless the columns are moved to their upper limits. In this event the member 83 on the outer column 12 will engage the spring 82 on the rod 80 and cause the latter to lift the yoke 77 sufficiently to return the tubes to horizontal circuit breaking position, regardless of the fact that the pedal may still be held in lowered position. It will be seen therefore that since the segments 39 and 40 are free to rotate on their pivots 43, and since the tubes are fixed with respect to said pivots the resistance of the springs 52 must be overcome to permit relative movement between the segments and tubes or movement from the normal position of said parts as shown in Fig. 5 to the position shown in Fig. 6.

If instead of depressing pedal 59, the opposite pedal 58 be depressed to lower the chair columns, the lug 83 on column 12 will engage the yoke 77 to operate the switch, provided the pedal is not released before the column approaches its lowermost position. In this case the tubes will be swung about the axes of the segments to the horizontal circuit breaking position shown in Fig. 6 while the segments 39 and 40 will remain inclined upwardly as shown. The lug 83 on the descending column in this case constitutes the operating means for the switch since when it reaches the yoke 77 it begins to move it downwardly to cause the bell-crank levers 44 to shift the segments 39 and 40 and the tubes thereon from the position shown in Fig. 5 to that shown in Fig. 6, the segments remaining in the inclined position shown for the reason that the pedal is still held in lowered position by the operator. However, as soon as the operator releases the pedal the segments will be automatically returned to normal position by the action of the spring 73 which returns the gear 64 to normal position thereby operating gear segment 67 which in turn operates segment 40 with which segment 39 is operatively connected.

It will be understood that when the yoke 77 is operated by lug 83 on the descending column 12 to return the mercury tubes to circuit break-

ing position, said yoke will be in an elevated position above that shown in Fig. 11, the lug being shown in its lowermost position in this figure. The position of the yoke shown in Fig. 13 is that to which it is moved by depressing either pedal 59 or 71 to shift the tubes to the circuit closing position shown in Figs. 7 and 13, in which position the motor will operate to lift the chair columns. If it is desired to lower the chair columns either pedal 58 or 72 will be depressed. If the operator is standing at the back of the chair he can effect raising and lowering of the columns by respectively depressing pedals 59 and 58 and if he is positioned at the right side of the chair as viewed in Fig. 8, depression of pedals 59 and 72 respectively will cause the motor to raise and lower the chair. Likewise if the operator is at the left of the chair depression of pedal 71 will result in raising of the columns and depression of pedal 58 will result in lowering of the same. It is evident therefore that pedals 58 and 71 constitute one set for effecting the up and down movements of the chair sections and pedals 59 and 72 constitute another set, and that pedals 58 and 59 constitute still another set, all for controlling the motor circuits and therefore the movements of the columns and the chair seat to be raised and lowered thereby.

30 I claim as my invention:

1. The combination with a chair base and a reciprocally mounted section thereon, mechanism for raising and lowering said section including an electric motor, of a mercury controlled switch including mercury holding means for controlling the motor circuit, means for manually moving said mercury holding means to close the circuit and means controlled by the section for moving the mercury holding means to circuit breaking position when the section is moved to a predetermined position.

2. The combination with a chair including a reciprocally mounted section and electrically driven power means operatively associated with said section arranged to operate in reverse directions, of a switch adjustable to reverse the circuit of said power means, manually operable means for reversing said switch and means controlled by said section for operating the switch to break the circuit when the section is moved to a predetermined position.

3. The combination with a chair base having a reciprocally mounted section thereon and a reversible electric motor for operating said section, of a fluid contact switch having circuit connections with said motor, oscillatory supporting means for said switch means for operating said switch supporting means to move the switch to different circuit closing positions whereby to effect reversal of the motor, and means under the control of said section arranged in different predetermined positions thereof to effect movement of the oscillatory supporting means to move the switch to circuit breaking position whereby to discontinue operation of the motor.

4. The combination with a chair base having a vertically movable section thereon and a reversible electric motor for operating said section, of adjustable switch means having circuit connections with said motor, means for manually adjusting said switch means to effect reversal of the motor circuit device operatively connected with said adjustable switch means including a member disposed adjacent one side of the movable section, and a part movable with

the section arranged in different predetermined positions of the latter to operate said member whereby to break the motor circuit.

5. The combination with a chair base including a reciprocally mounted section and electrically driven power means operatively associated with said section for reciprocating the same, of circuit control means electrically connected with said power means comprising a pair of adjustable switch units normally in circuit breaking position, manually operable means for simultaneously moving said units to either of two circuit closing positions whereby to start operation of said power means operating means for moving said units to circuit breaking position, and means on said section arranged when the section is moved to different predetermined positions to shift said operating means whereby to move said units to circuit breaking position.

6. The combination with a chair base and a reciprocally mounted section thereon, a reversible electric motor operatively connected with said section, of a pair of relatively movable mercury tube switch units each included in the motor circuit, operating means for simultaneously moving said units one relative to another and each in either of two directions during relative movement to close the motor circuit and means for returning the units to normal circuit breaking position when the operating means is released.

7. The combination with a chair base and a reciprocally mounted section thereon, a reversible electric motor operatively connected with said section, of a pair of mercury tube switch units each included in the motor circuit, manually operable means for simultaneously moving said units in either of two directions to close the motor circuit, spring means for returning the units to normal circuit breaking position when the operating means is released, means responsive to the movement of the section when the latter is in a predetermined position operating to move said units to circuit breaking position when the manually operable means is held against release and means for retarding the movement of the units to normal position by the spring means.

8. The combination with a chair base and a reciprocally mounted section thereon, a reversible electric motor operatively connected with said section, of a pair of mercury tube switch units included in the motor circuit, manually controlled operating means for simultaneously moving said units in either of two directions to close the motor circuit and means for moving said switch units to circuit breaking position upon movement of the chair section to different predetermined positions, said means being operated by the section when it is moved to either of said positions.

9. The combination with a chair base and a reciprocally mounted section thereon, a reversible electric motor operatively connected with said section for moving it upon the base between predetermined limits, of means for reversing the motor circuit including a tiltable tube having gravity responsive means therein for making and breaking the circuit, manually operable means for said tube and additional operating means associated with said manually operable means for moving the tube to circuit breaking position, said additional operating means being operated by the section upon reaching said predetermined limits.

10. The combination with a chair base and a reciprocally mounted chair section thereon, a reversible electric motor operatively connected with said section for moving it upon the base between predetermined positions, of a pair of cooperating switch units included in the motor circuit and arranged to swing upon the base to and from different circuit closing positions, means for manually operating said units to said different circuit closing positions, an actuating device for moving said switch units to circuit breaking position, and spaced operating members upon said section arranged to operate the actuating device to break the circuit when the section is moved to said predetermined positions. 80
11. The combination with a chair base and a reciprocally mounted section thereon, mechanism for raising and lowering said section including an electric motor, a mercury tube switch for controlling the motor circuit comprising relatively movable mercury holding containers with contacts therein for cooperation with the mercury in relatively different positions of the containers whereby the circuit is closed with the containers in either of said positions, means for manually operating the switch to move the containers to either of said circuit closing positions, and means actuated by the section at either of its limits of movement for moving the containers from either circuit closing position to circuit breaking position. 85
12. The combination of a chair base and a reciprocally mounted chair section thereon, a reversible electric motor operatively connected with the section for moving it upon the base between predetermined positions, of a pair of cooperating switch units included in the motor circuit and mounted for movement upon the base to and from circuit closing position, actuating elements for the units connected for operation one by another, the latter having an operating part therfor, manually operable means connected with said part to effect movement of said units to circuit closing position, and means under the control of said section arranged in different predetermined positions thereof to move said units to circuit breaking position. 90
13. The combination with a chair base having a reciprocally mounted section thereon and a reversible electric motor for operating said section, of a switch comprising spaced oscillatory supports having thereon cooperating switch units for reversing the motor circuit, means for manually operating said supports to effect reversal of the circuit, and additional operating means for the supports responsive to the up and down movements of the section whereby to break the circuit in different predetermined positions of the section. 95
14. The combination with a chair base having a reciprocally mounted section thereon and a reversible electric motor for operating said section, of a switch comprising spaced oscillatory supports having thereon cooperating switch units for reversing the motor circuit, means for manually operating said supports to effect reversal of the circuit, and additional operating means for the supports including a link between the supports having an actuating part responsive to the movement of said section in a predetermined position thereof whereby to break the circuit. 100
15. The combination with a chair base having a reciprocally mounted section thereon and a reversible electric motor for operating said section, of a switch comprising cooperating units for reversing the motor circuit, oscillatory supports for said units, a pedal operatively connected with said supports for moving the switch units to effect reversal of the circuit, additional operating parts connected with said supports, and a connection between said parts provided with an operating element arranged to be actuated by said section in a predetermined position thereof whereby to break the motor circuit. 105
16. The combination with a chair base having a reciprocally mounted chair raising section thereon and a reversible electric motor for operating said section, of a switch comprising a pair of fluid contact units interposed in the circuit connections of the motor for cooperation in different predetermined positions to complete the circuit, a movably mounted support for each of said units, manually controlled means for moving said supports whereby to move said switch units from normal circuit breaking position to said predetermined circuit closing positions, spring means for returning said supports to normal position, means for retarding the action of the spring means to afford a relatively slow return movement of said units, and additional operating means for said movably mounted supports responsive to the movement of said section in a predetermined position thereof whereby to break the motor circuit. 110
17. The combination with a chair base having a reciprocally mounted chair raising section thereon and a reversible electric motor for operating said section, of a pair of oscillatory supports on the base having intermeshing gear segments thereon, a fluid contact switch unit carried by each support, said units being included in the motor circuit and normally held in circuit breaking position by said supports, a foot pedal operatively associated with one of said segments, spring means for returning the pedal and segments to normal position, an operating arm associated with each of said supports, a link connected with said arms for operating the same, and an actuating member for the link arranged for operation by the chair section upon failure to release the pedal when the section is moved to a predetermined position whereby the switch units are moved to circuit breaking position. 115
18. The combination with a base having a reciprocally mounted member thereon and a reversible electric motor for operating said member, of a switch having circuit connections with said motor, a pair of spaced pedals and an intermediate pedal mounted on the base, operating means for the switch including an actuating part connected with one of the spaced pedals for operation thereby, an element operatively connected with said part adapted to be actuated by the intermediate pedal, actuating means for said element connected with the other of said spaced pedals for operation thereby, and additional operating means under the control of said reciprocally mounted member for automatically operating said switch in different predetermined positions of said member to break the circuit whereby to discontinue operation of the motor. 120
